HAIR CURLERS

Terry S. Lubore, West Hyattsville, Md.

Application June 2, 1958, Serial No. 739,248

11 Claims. (Cl. 132—41)

This invention relates to improvements in hair curlers, and more particularly to curlers used to impart a permanent curl or wave in human hair.

While some human hair is naturally wavy, it is well known that many people have hair which lacks a wavelike form. Many people, especially women, prefer to have hair which has a wavelike form, as it enhances their beauty.

There are many processes known for imparting a permanent wave to hair. Most of such processes have the following features in common: (1) small strands of hair are separately coiled about a curler; (2) while so coiled they are wetted by a suitable cold waving solution applied to the outer coils of the hair; and (3) after the waving solution has been effective for a desired length of time, a neutralizing solution is applied. In this process the outer layers of the coil, which is that portion of the hair strand nearest the scalp, receives a more thorough impregnation than the inner layers near the curler and thereby receives a tighter curl. This is exactly the reverse of the desired effect, since a more pleasing wave is produced when the outer portions of the hair strand receive the tighter curl.

In this operation it is almost impossible to thoroughly saturate the coils of hair without wetting the scalp with the waving solution and even having the solution dripping into the face of the subject. This is undesirable since the solutions are usually irritating to the skin and unpleasant or even dangerous in the eyes, nose or mouth.

An improved method has been devised in which a capsule containing hair waving solution is inserted into the hollow curler, which is broken when a hair retaining member, adapted to hold the coil of hair in position around the curler, is placed into position. This method suffers from the disadvantage that the treatment of each strand of hair is initiated when curled, and consequently each coil of hair is given a different period of treatment by the solution.

Another method has been devised in which the waving solution is carried in the body of the curler, and which is released by breaking the curler which releases the solution. While this method permits an equal length of treatment for each coil of hair, the curlers are destroyed to release the solution and cannot be reused.

It is an object of the present invention to overcome these disadvantages, in providing a curler which may be repeatedly used, and which permits substantially the same period of treatment for each coil of hair.

It is a further object of this invention to provide a hair curler in which a frangible or pierceable capsule may be inserted within a cage in the curler, either before or after winding the hair in a coil, which may be broken to saturate the hair, and the broken capsule may be removed and a new capsule inserted without disturbing the hair retaining means.

It is a further object of this invention to provide a hair curler in which a capsule may be broken within the

coil of hair in order to impregnate the hair with a waving solution, removed, and replaced by another capsule containing a neutralizing solution, which is also broken, all without disturbing the hair retaining means.

It is a further object of the invention to provide a cage within the hair curler which is adapted to receive, for breaking therein, capsules or containers of different length, permitting the application of smaller or larger applications of hair waving solution or neutralizing solution to each coil of hair wound on the curler.

It is a further object of the invention to provide a curler having flexible portions which are adapted to be flexed to break a container of hair treating solution within the curler.

It is a further object of the invention to provide a curler having flexible portions carrying container breaking means, which may fracture and/or pierce the walls of a container containing a hair treating solution within the curler.

It is a still further object of the invention to provide a hair curler which may be used by inexperienced persons to provide a wave which is comparable to that of a professional.

These and other objects and advantages will become more apparent as the description of the invention proceeds.

For a more detailed description of the invention, reference is made to the accompanying drawings in which the same reference characters are used to designate similar parts; and in which

Fig. 16 is a fragmentary view of another modification of a locking means for the hair retainer bar member permitting the insertion and removal of a container for hair treating solution; and

Fig. 17 is an end view of Fig. 16.

In the description which follows, the term "breaking," with reference to the capsule or container of hair treating solution, is intended to cover either a fracture of the wall or a piercing of the wall to permit the escape of the solution.

Referring to the modification shown in Figs. 1 to 7, the curler comprises a body member 20 about which a strand of hair is intended to be coiled, and a retainer bar member 22. The retainer bar member 22 is swivelly connected at 24 to the body member, which permits a strand of hair to be coiled about the body member, after which the coil of hair is held from uncoiling by locking the retainer bar member in closed position as shown in Fig. 4. For this purpose the retainer bar member is provided with a locking lug 34.

The body member 20 comprises a pair of end members 26 and 28 which are held in spaced relation by a plurality of laterally flexible spaced bars 30. While four bars are shown, it is obvious that a greater or lesser number may be used. The end member 26 is solid in construction, and provides a supporting member for the swivelled end of the retainer bar member 22. The end member 28 is provided with an axially extending opening 40 which communicates with the space between the spaced bars 30. It is thus seen that the spaced bars 30 and end members 26 and 28 provide a cage for the reception of a container 44 of hair treating solution 45. One end of this cage is closed by the end member 26, while the other end of the cage is open at 40 for receiving and withdrawing the container 44.

The free end of the retainer bar member 22 is provided with a bifurcated flange 36, each leg of which carries a locking lug 34. These locking lugs engage recesses 38 in the end member 28. As clearly shown in Fig. 2, the recesses 38 are arranged in parallel pairs on opposite sides of the opening 40, whereby the opening 40 is always unobstructed when the retainer bar member is locked to permit the delivery and withdrawal of a container 44 of hair treating solution.

The container 44 is in the form of an elongated capsule, filled with a hair treating solution 45, which may be either a hair waving solution or a neutralizing solution. One end of the container is provided with a tab 46 which extends through the opening 40 to a position in which it can be readily grasped to withdraw the broken container.

The retainer bar member 22 is provided with a plurality of spaced breaking members 42 directed toward the body member 20. The outer ends of the spaced breaking members 42 are pointed, for a purpose to be set forth hereafter. The recesses 38 in the end member 28 are positioned relative to the spaced rods 30 in such a manner that the spaced breaking members 42 may pass through the spaces formed between the rods 30 when the retainer bar member 22 is clamped or locked in hair retaining position (Figs. 4, 5 and 6).

The spaced rods 30 are provided, on their outer surfaces, with a plurality of small, spaced, pointed members 32 for maintaining the coiled strand of hair spread about the body member to assure a tight curl.

The body member 20 and the hair retainer bar member 22 of the curler are made of a material having inherent flexible characteristics, such as wood or plastic. The container 44 is made of a frangible material such as glass or plastic, having characteristics which encourage breaking in long lines rather than shattering in small pieces. It may also be made of a shatterable material, if desired, in which case it would be enclosed within a porous, non-permeable, sleeve, such as nylon. The container may also be made of a non-shatterable material which may be punctured at a number of places to release the contents.

The spacing of the rods 30 and their flexible characteristics are such as to form a cage of slightly smaller cross section than that of the container 44, so that when the container is inserted into the cage, it is frictionally held therein, but may be removed with but slight effort. The spaced members 42, hereinafter termed the "breaking points," are made of such length that, when the retainer bar member 22 occupies its hair retaining position

as shown in Figs. 4 and 5, the outer ends thereof contact, without sufficient pressure to break, the wall of the container 44.

The operation is as follows: The retainer bar member 22 is swung to one side and a strand of hair is coiled about the body member 20, as shown in Fig. 4, after which the retainer bar member is brought into its hair retaining position and locked in place by forcing the lugs 34 into the recesses 38. The bifurcated flange 36 is resilient in order for the lugs to pass over the end 28 and to resiliently hold the lugs in their recesses. This process is repeated with other strands of hair until all of the hair, or so much thereof as is desired to be curled, is in place around the curlers. The containers 44 may be inserted through the openings 40 either before or after the strands of hair are coiled thereon. Containers having a waving solution are first inserted. When the curling or coiling operation is completed, the capsules may be broken by flexing the retainer bar member 22, as shown in Fig. 6, by grasping the body member 20 and the retainer bar member 22 between the fingers and thumb and in applying sufficient pressure to fracture the container if a frangible container is used, or to pierce the container wall at a plurality of points if a puncturable container is used, as shown in Figs. 6 and 7. If a puncturable container is employed, it is within the scope of this invention to provide points on the breaking members having ribs or other means thereon which will not interfere with the free outflow of the solution. All of the containers are broken, one immediately after the other, whereby the solution will escape from the capsules or containers about the same time to thoroughly saturate the coils of hair. If the container is punctured, the curler may be oriented to facilitate the escape of the solution by gravity. The waving treatment for all of the coils of hair is thereby initiated at the same time, so that it is easy to time the duration to assure a sufficient length of treatment to produce the desired wave for the entire head of hair. Having broken the capsules or containers and having allowed sufficient time to drain the contents thereof, the empty containers can readily and quickly be removed by grasping the tabs 46 and withdrawing them through the openings 40, without interfering with the locking of the hair retainer bar member 22. Other containers having a neutralizing solution therein can immediately be inserted through the openings 40. When the coils of hair have undergone the treatment by the waving solution for the required length of time, such solution may be rinsed with water as preferred, and the capsules containing the neutralizing solution may then be broken, which will release such solution within the coiled hair.

The invention may also be practiced by using containers having both a waving solution and neutralizing solution therein.

Containers having different lengths, containing different quantities of waving solution or neutralizing solution, may be employed for treatment of hair requiring more or less solution, or in cases where different thicknesses of strands are coiled.

In the modification shown in Figs. 8 and 9, a plurality of breaking means are carried by one or more of the bars 30. As illustrated, each of the bars 30 is provided with a plurality of breaking means 50 in the form of pointed members extending inwardly into the cage, which are of such length that they engage, with but slight frictional force, the wall of a container 44, which force is sufficient to retain the container against axial movement but is insufficient to break it. This modification operates similarly to that shown in Figs. 1 to 7, and the container is broken by applying a crushing force against the bars 30 sufficient to break the container 44.

In the modification shown in Figs. 10 and 11, the container is carried by the retainer bar member, and the breaking means are carried by the body member. For

this purpose the retainer bar member 22 is provided with several pairs of opposed clamping lugs 54, made integral with the retainer bar member, and serving, with the bar member, to form recesses having surrounding walls which engage and retain the container 44 between the bar and the body member when the retainer bar member is in its locked position. Each rod 30 is provided with a plurality of spaced, pointed, breaking means 52 which extend outwardly to engage a wall of the container 44 when the retainer bar member is locked, as shown in Fig. 10. In this form of the invention, the recesses 38, which lockingly receive the lugs 34, are located in such a position that a rod 30 is directly aligned with the retainer bar member 22 when the lugs 34 enter the recesses, with the points on the breaking means 52 in light engagement with the container 44. Like the other modifications, the container is broken by forcing the flexible retainer bar member 22 and the flexible rods 30 toward each other. In order to replace a container 44, the retainer bar member is unlocked and slightly opened, whereupon the broken container may be removed and replaced by a new container.

In the modification shown in Figs. 12 and 13, the retainer bar member 22 is provided with an elongated recess 68 on the inner side thereof facing the body member 66, adapted to receive a container 44. An elongated resilient clip 56, having its ends reversely bowed as shown at 55 and 57, holds the container 44 within the recess 68. The bowed end 57 is secured to the retainer bar member as by riveting at 58. The other bowed end 55 is provided with a hook 61 adapted to engage a lug 62 on the end of the retainer bar member. The free end of the resilient clip 56 has a catch 63 thereon adapted to be engaged by a finger nail to release the hook 61 from the lug 62. The mid portion of the resilient clip 56 has a plurality of projections or breaking points 64 extending therefrom toward the retainer bar member which engage the wall of the container 44 with insufficient force to break the container, when the resilient clip is locked.

In the operation of this modification, the capsule or container 44 is inserted in the recess 68 and the resilient clip 56 is locked in position by pressing the bowed end 55 toward the retainer bar member 22 so that the hook 61 slips over the lug 62, which operation brings the breaking points 64 into contact with the wall of the container 44. A strand of hair is then coiled about the body member 66, as in the other modifications, after which the retainer bar member 22 is locked in position by forcing the lug 34 on the end 36 to engage one of the recesses 38. The container is broken by applying pressure against the retainer bar member, which releases the hair treating solution 45, permitting it to flow downward and saturate the coil of hair. In order to remove the broken container, the retainer bar member 22 is unlocked, and by engaging the catch 63 with the finger nail, the hook 61 can be removed from the lug 62. A new container can be quickly slipped in place after the broken container is removed, and the resilient clip again locked closed. This modification differs from the formerly described modifications in that the hair treatment solution is applied to the outer part of the coiled hair instead of within the coils.

A modified form of the free end of the retainer bar member 22 is shown in Figs. 14 and 15. This modification shows the retainer bar member as being provided with a flange 70 of sufficient length to cover the end 28 of the body member. The outer end of the flange is provided with a lug 74 extending transversely of the flange and directed toward the end 28 to engage a selected recess 76 of a plurality of recesses on the end 28. An opening 72 extends through the flange 70 and is positioned to be coaxial with opening 40 in the end portion 28 when the lug 74 is locked in the recess 76, so as to permit the insertion and removal of a container.

Figs. 16 and 17 show another modification of the locking means for the retainer bar member. In this form of the invention the flange 70' is relatively short, so that its extremity 78 does not extend over the opening 40, permitting an uninterrupted insertion and removal of the container 44.

From the foregoing, it is seen that a novel hair curler has been described which permits the application of measured quantities of hair treating solution to coiled 10 strands of hair, and in which all containers may be broken at about the same time, permitting an equal length of treatment for each coil of hair, thus assuring a more uniform wave of hair on all parts of the head.

It is to be understood that while several forms of the invention have been disclosed, other modifications are readily apparent within the scope of the appended claims.

I claim:

1. A curling rod comprising: an elongated body member adapted to receive a coil of hair; an elongated retainer bar member; each member having means on one end pivotally mounting the retainer bar member on one end of the body member, and having means on the other end releasably locking the retainer bar member to the body member in closed position; at least one of said members having laterally flexible characteristics; means carried by one of said members for removably receiving an elongated breakable container of hair treating solution having a side wall and end walls; and breaking means carried by said laterally flexible member between said ends and projecting laterally thereof, said breaking means having a length sufficient to contact, but not break, the side wall of the container between the ends thereof when the retainer bar member is in locked position.
2. A curling rod as recited in claim 1, in which the means for removably receiving an elongated breakable container of hair treating solution is carried by the retainer bar member, and the laterally projecting breaking means is carried by the body member.
3. A curling rod comprising: an elongated body member adapted to receive a coil of hair; an elongated retainer bar member; each member having cooperating means in one end pivotally mounting the retainer bar member, and having cooperating means on the other end releasably locking the retainer bar member in a closed position to the body member; said body member being hollow and having an unrestricted opening at all times through one end thereof through which an elongated breakable container of hair treating solution may be inserted and removed when the retainer bar member is in its locked position; one of said members having laterally flexible characteristics; and breaking means carried by said laterally flexible member between the ends thereof and projecting laterally thereof, said breaking means having a length sufficient to contact, but not break, the side wall of the container between the ends thereof when the retainer bar member is in locked position.
4. A curling rod as recited in claim 3, in which the breaking means are carried by the body member.
5. A curling rod adapted to receive a coil of hair, comprising: an elongated body member, said body member being hollow to removably receive a breakable container of hair treating solution, and having an opening in a side wall thereof; an elongated retainer bar member having flexible characteristics; each member having cooperating means on one end pivotally mounting the retainer bar member, and having cooperating means on the other end releasably locking the retainer bar member to the body member in closed position; said retainer bar member having, between the ends thereof, breaking means projecting into the opening in the body member when the retainer bar member is in its locked position, said breaking means having a projecting length sufficient to contact, but not break, the side wall of the container.

tainer between the ends thereof when the retainer bar member is in its locked position.

6. A curling rod as recited in claim 5, in which the body member includes a pair of end members separated by spaced ribs forming the opening in the side wall.

7. A curling rod as recited in claim 5, in which the hollow body member has an unrestricted opening at all times through one end thereof, through which the container may be inserted and withdrawn when the retainer bar is in locked position.

8. A curling rod as recited in claim 7, in which the unrestricted opening is through the end having the locking means.

9. A curling rod as recited in claim 8, in which the locking means on the end of the retainer bar member includes a bifurcated flange straddling the unrestricted opening in the body member when the retainer bar member is in locked position.

10. A curling rod as recited in claim 8, in which the locking means on the end of the retainer bar member includes a flange having an opening therethrough in a position to align with the unrestricted opening in the body member when the retainer bar member is in locked position.

11. A curling rod as recited in claim 8, in which the locking means on the end of the retainer bar member includes a flange which, in locked position, is too short to restrict the unrestricted opening of the body member.
